STRINGER TAPE FOR SEPARABLE
FASTENERSDavis Marinsky, Bronx, N. Y., assignor to White-
hall Patents Corporation, New York, N. Y., a
corporation of New York

Application October 31, 1936, Serial No. 108,578

3 Claims. (Cl. 2—265)

This invention relates to separable fasteners and particularly to the stringer tapes of fasteners; and the object of the invention is to provide a single, unitary woven tape having a beaded edge portion with two strips extending from said edge portion, one of said strips having a weakened area extending longitudinally thereof to cause the same to fold readily in one direction upon the body portion of the tape to form a covering or cushioning portion adapted to overlie the inter-engaging and coupled links of two stringers; a further object being to provide a stringer tape of the class described having means for cushioning and protecting the links of the stringer over the body of a person when such devices are used on various kinds and classes of apparel; a further object being to provide a stringer tape of the class described, one or more portions of which include a pile of fabric forming cushioning sections or areas thereon to provide a comfortable mounting of fastener devices directly adjacent the body of a wearer when the fastener is applied upon predetermined articles of apparel; and with these and other objects in view, the invention consists in a tape of the class described and for the purpose specified, which is simple in construction and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of a part of two stringer tapes arranged in coupled relationship.

Fig. 2 is a partial section on the line 2—2 of Fig. 1.

Fig. 3 is a view similar to Fig. 2 showing a modification.

Figs. 4 and 5 are views similar to Fig. 2 showing other modifications; and,

Fig. 6 is a sectional and perspective view of another form of construction which I employ.

In Figs. 1 and 2, I have shown at 10 and 11 two stringer tapes of a separable fastener, each tape having a beaded edge portion 12 and 13 forming part of a reinforced or ribbed edge portion 14 and 15, to which the links 16 and 17 are attached.

The tape 10 differs from the tape 11 in the inclusion of a supplemental flap portion 18 as an integral part of the tape 10, or, in other words, woven integrally therewith. This flap extends outwardly from the ribbed edge 14 and is free from the attaching end portion 10a of the tape 10. The flap 18 joins the tape 10 in a weakened

portion 19 which may be formed by eliminating some of the longitudinal threads, the purpose of which is to provide what might be termed a hinged coupling which will serve to normally support the flap 18 at all times upon the inner or lower surface of the links 16, 17, or in other words, between said links and the body of the wearer when applying fasteners of this type and kind to articles of apparel which contact directly with the body of the wearer, such for example, on various types of undergarments, including corsets, girdles, brassières and the like, as well as on various kinds of shirts, including polo shirts which are worn directly upon the body of the wearer.

It is desirable to arrange the guard cushioning or protecting flap 18 closely within the transverse boundaries of the links 16 and 17 in order to provide clearance for the line of stitching employed in attaching the fastener stringers to the garments at points substantially adjacent the references x, x2, as seen in Fig. 2 of the drawing, without interference with the flap 18 and so that the slider commonly employed in fasteners of the kind under consideration is free to move longitudinally of the links of the stringer and within the flap 18. In some instances, the flap 18 may be composed of a lighter weave of fabric than employed in the part 10a as this flap is subjected to no particular stress or strain.

In Fig. 3 of the drawing, I have shown a slight modification of the structure shown in Fig. 2, wherein a flap 18a similar to the flap 18 is applied to or constitutes a part of the tape 11 to provide a means for covering the outer surfaces of the links as well as the inner surfaces thereof, which may be desirable from the standpoint of appearance on certain kinds and classes of articles of apparel. In this connection, it will be understood that the flap 18a may be woven integrally with the stringer tape 11, or, if desired, may constitute an independent strip attached thereto by stitching.

In Fig. 4 of the drawing, I have shown another slight modification of the construction shown in Fig. 2 wherein the flap 18 includes a woven pile 18b arranged upon the inner or lower surface of the flap to form a cushion adapted to rest against the bottom. This type of construction will be especially adaptable for use on garments or articles of apparel which are arranged firmly upon the body such as corsets, girdles and the like. This construction will cushion the links from the body of the wearer and prevent or obviate undesirable binding which would otherwise be experienced.

The structure shown in Fig. 6 of the drawing

differs from that shown in Fig. 4 simply in restricting the pile of the fabric to two rows or ribs 18c and 18d disposed adjacent the free and attached side portions of the flap 18. This type of construction will produce a more resilient cushion and will be suitable for many uses of devices of the kind under consideration.

In Fig. 5 of the drawing, I have shown another method of protecting and cushioning the fastener stringers, and in this construction, the stringer tapes 20 and 21 are provided on their inner surfaces with a raised fabric pile 22, 23 respectively, the pile being of sufficient height to provide means to cushion the mounting of the separable fastener upon the body of the wearer and to space the coupling links 24, 25 therefrom. The height of the pile may be varied to suit different conditions and uses, and if desired, a flap 18 as shown in Fig. 2, or flaps similar to those shown in Figs. 4 and 6 may also be employed in conjunction with one of the stringer tapes for additional protection.

From the foregoing, it will appear that the distinctive feature of my invention resides in the provision of means on the tape or tapes of a separable fastener to cushion and otherwise cover and protect the fastener from coming in contact with the body of the wearer and in employing the cover flap, the provision of means consisting of the weakened portion therein for maintaining said flap in juxtaposition to the links of the fastener stringers at all times.

Having fully described my invention, what I claim as new and desire to secure by Letters Patent, is:

1. A stringer tape for separable fasteners comprising an elongated ribbon-like strip of woven fabric, one side edge of the strip being fashioned to permit attachment of coupling links thereto, that portion of the strip extending from said edge being divided into a mounting portion and a flap portion, said flap portion being arranged over and extending outwardly beyond the first named edge portion of said strip, said flap joining the strip in a weakened portion, said weakened portion being at the first side edge of the strip and adjacent the position of the coupling links when

attached thereto, and said weakened portion being of sufficient width to compensate for the height of said links projecting to the side of the tape on which the flap is arranged so that the flap will lie snugly upon the surface of said links. 5

2. A stringer tape for separable fasteners comprising an elongated ribbon-like strip of woven fabric, one side edge of the strip being fashioned to permit attachment of coupling links thereto, that portion of the strip extending from said edge 10 being divided into a mounting portion and a flap portion, said flap portion being arranged over and extending outwardly beyond the first named edge portion of said strip, said flap joining the strip in a weakened portion, said weakened portion 15 being at the first side edge of the strip and adjacent the position of the coupling links when attached thereto, said weakened portion being of sufficient width to compensate for the height of said links projecting to the side of the tape on 20 which the flap is arranged so that the flap will lie snugly upon the surface of said links, and one surface of said flap including a body of cushioning material extending longitudinally thereof.

3. A stringer tape for separable fasteners comprising an elongated ribbon-like strip of woven fabric, one side edge of the strip being fashioned to permit attachment of coupling links thereto, that portion of the strip extending from said edge being divided into a mounting portion and a flap 30 portion, said flap portion being arranged over and extending outwardly beyond the first named edge portion of said strip, said flap joining the strip in a weakened portion, said weakened portion 35 being at the first side edge of the strip and adjacent the position of the coupling links when attached thereto, said weakened portion being of sufficient width to compensate for the height of said links projecting to the side of the tape on which the flap is arranged so that the flap will 40 lie snugly upon the surface of said links, one surface of said flap including a body of cushioning material extending longitudinally thereof, and said body of cushioning material being arranged in independent rows disposed adjacent the side 45 portions of the flap.

DAVIS MARINSKY.
